United States Patent Office.

JAMES McCANN, OF ST. LOUIS, MISSOURI.

Letters Patent No. 89,492, dated April 27, 1869.

IMPROVED RETORT FOR PREPARING CHARCOAL FOR RECTIFYING SPIRITS, &c.

The Schedule referred to in these Letters Patent and making part of the same.

To all whom it may concern:

Be it known that I, JAMES McCANN, of St. Louis, in the county of St. Louis, and State of Missouri, have invented a new and useful improved Retort for Preparing Rectifying-Charcoal, of which the following is a full, clear, and exact description, reference being had to the annexed drawing, making a part of this specification, in which—

Figure 1 represents a vertical sectional elevation of my invention.

Figure 2 represents a bottom view of the rod of same.

Similar letters indicate like parts.

The object of my invention is to shorten and make more certain the process of preparing charcoal for rectifying-purposes.

It is well known that by the use of the common retort, the fire is a long time in reaching the centre of the coal, and the escape of the gas generated is more or less retarded by the compactness of the coal, caused by its settling after burning for a while. To stir it from the top would only increase this difficulty. I have, therefore, sought by my invention to improve the draught through the centre of coal, and to prevent the coal from becoming so compact as to impede the escape of the gas.

The retort A is made in the usual manner, with no bottom, and rests on legs b b' b'', b' only being seen in fig. 1, so that the air may have free access.

A rod of iron, C, terminating in radial arms 1 5, fig. 1, and 1, 2, 3, &c., fig. 2, the length of the arms being somewhat less than the radius of the retort—is placed

in the centre of the retort, the arms resting on the ground, as seen in fig. 1. The retort is then filled with charcoal, and the fire kindled on top.

Now, in the ordinary retort, the coal is apt to burn only around the circumference, while the centre is untouched for a long time by the fire; but by the use of the rod, a draught is created through the centre, which in a measure overcomes the difficulty.

After the fire has passed down the sides and along the bottom, I, by means of a pulley connected with the ring e, or other device, raise the rod entirely out of the retort, of course stirring and mixing the dead and live coal by the operation, and loosening the whole mass, so as to give free exit to the generated gas.

After it is sufficiently burned, I put on the cover, which rests on the shoulders c c', and seal the retort up in the usual manner to cool.

By the use of this apparatus, I claim I can more surely and rapidly expel the gas, and consequently make a better rectifying-coal than with the old retort.

I do not claim any originality in the construction of the retort; but

What I do claim as my invention, and desire to secure by Letters Patent, is—

The combination, with the retort A, of a forked rod, C, or its equivalent, when constructed and operating substantially as and for the purpose specified.

JAMES McCANN.
